CLAIM

The ornamental design for a nib holder for coordinate input instrument as shown and described.

DESCRIPTION

FIG. 1 is a top-front-left perspective view of a nib holder for coordinate input instrument according to an embodiment of our new design;

FIG. 2 is a bottom-rear-right perspective view thereof;

FIG. 3 is a front elevational view thereof;

FIG. 4 is a rear elevational view thereof;

FIG. 5 is left side elevational view thereof;

FIG. 6 is a right side elevational view thereof;

FIG. 7 is top plan view thereof;

FIG. 8 is a bottom plan view thereof; and,

FIG. 9 is a partially exploded environmental view thereof, shown with a coordinate input instrument.

The broken lines in the figures depict portions of nib holder for coordinate input instrument that form no part of the claimed design.
